(57) CLAIM

We claim the ornamental design for a detachable shelf for mounting onto televisions and other accessories, as shown and described.

DESCRIPTION

FIG. 1 is a perspective view of a detachable shelf for mounting onto televisions and other accessories showing my new design, the broken line disclosure of a television being for illustrative purposes only and forming no part of the claimed design;

FIG. 2 is the right perspective view of FIG. 1;

FIG. 3 is the left perspective view of FIG. 1;

FIG. 4 is the front perspective view of FIG. 1;

FIG. 5 is the back perspective view of FIG. 1;

FIG. 6 is a top view of FIG. 1; and,

FIG. 7 is a bottom view of FIG. 1.
